UNITED STATES PATENT OFFICE

154,517

DESIGN FOR A ROCKER FOR CHILDREN

Edward Strack, Bloomfield, N. J.

Application May 12, 1947, Serial No. 139,002

Term of patent 14 years

(Cl. D15—6)

To all whom it may concern:

Be it known that I, Edward Strack, a citizen of the United States of America, residing at Bloomfield, in the county of Essex and State of New Jersey, have invented a new, original, and ornamental Design for a Rocker for Children, of which the following is a specification, reference being had to the accompanying drawing, forming part thereof.

Fig. 1 is a perspective view of a rocker for children embodying my new design. Both sides of the rocker are the same.

Fig. 2 is a side elevational view;

Fig. 3 is a top plan view; and

Fig. 4 is a front elevational view thereof.

I claim:

The ornamental design for a rocker for children, substantially as shown and described.

EDWARD STRACK.
